UNITED STATES PATENT OFFICE.

LOUIS TLUCKA, OF BOONTON, NEW JERSEY, ASSIGNOR TO VAN RAALE COMPANY, INC., OF NEW YORK, N. Y., A CORPORATION OF NEW YORK.

FANCY KNITTING ATTACHMENT FOR KNITTING MACHINES.

Application filed June 18, 1921. Serial No. 473,460.

To all whom it may concern:

Be it known that I, LOUIS TLUCKA, a citizen of the United States, and a resident of Boonton, county of Morris, and State of New Jersey, have invented a new and useful Improvement in Fancy Knitting Attachments for Knitting Machines, of which the following is a specification.

The object of my invention is to provide an attachment of the type in question which may be applied to any suitable knitting machine and particularly those known as the "Cotton" type.

A further object is to provide a device which will enable the knitting machine to make lock stitches. These objects are accomplished by my invention, one embodiment of which is hereinafter more particularly set forth.

20 A further object of this invention is to provide a means for regulating the stitches formed by the usual form of knitting machine whereby suitable designs may be formed in stockings or other knitted articles.

25 For a more detailed description of my invention, reference is to be had to the accompanying drawings, forming a part hereof, in which—

30 Figure 1 is a front elevation of a portion of a machine embodying my invention and showing a portion of the knitting machine to which it is applied,

35 Figure 2 is an enlarged side elevation of my attachment, separated from the knitting machine,

Figure 3 is a plan view of the same,

Figure 4 is an end elevation of my attachment with parts removed to clearly reveal the structure,

40 Figure 5 shows a detail of construction relating to the chain feed mechanism, and

Figure 6 is a longitudinal section taken on the lines 6—6 of Figure 3, looking in the direction of the arrows.

45 Throughout the various views of the drawings, similar reference characters designate similar parts.

1 indicates my improved attachment which may be applied to any suitable machine, as a "Cotton" knitting machine of the character used for making "full fashioned" hosiery and which is driven by a main shaft 3 that is extended so as to drive my improved attachment. The knitting machine 55 is also provided with a knitting shaft 4

which carries transfer points 5 in the conventional manner. This shaft 4 is moved longitudinally to the right as shown in Figure 1 by a coil spring 6 which surrounds a portion of the shaft 4 and bears at one end 60 against a collar 7 which is fixed to the shaft and at its other end the spring bears against a portion 8 of the machine 2. The extreme end of this shaft 4, which is next the attachment 1, carries an adjusting screw 9 which 65 may be adjusted to suit the needs of the machine or to take up wear. My attachment 1 acts in opposition to the spring 6 so as to force the shaft 4 in the direction of its length, at suitable times, according to the 70 nature of the fancy work which is to be incorporated into the fabric of the stockings or other articles which are knitted by the machine.

My improved attachment 1 is mounted in 75 and on a suitable frame 10 in which the end of the main shaft 3 is suitably journaled. This main shaft 3 carries two double cams 11 and 12 and a single cam 13, which cams will operate according to the position of the 80 shaft 3, which has a sufficient longitudinal movement to enable the proper face of these double cams to become operative in a manner which will be described below.

The cam 13 is broad faced and always 85 works the same regardless of the position, longitudinally speaking, of the shaft 3 so that this cam is not affected by the longitudinal movements of this shaft, and this cam 13 engages a roller 14 mounted on a lever 15 90 that is pivoted on a fulcrum shaft 16 in the conventional manner. This shaft 16 is carried by suitable brackets 17 which rise from the frame 10.

The lever 15 carries a pawl 18 which is 95 adapted to engage a ratchet 19 which is fixed to a shaft 20 mounted in suitable bearings 21 which extend from the frame 10 of the machine. This shaft 20 also carries a drum 22 with sprocket wheels 23 fixed thereon and the drum 22 is fixed to the shaft 20 so that it turns with the shaft under the impulse of the pawl 18 on the ratchet 19. The sprocket wheels 23 engage a sprocket chain 24 which runs upwardly to an idle 105 pulley 25 mounted on a spindle 26 which is carried by a suspended hanger 27 from a support 28 that rises from the frame 10 of the attachment. This hanger 28 is adjustably mounted so that the slack in the chain 110

24 may be removed and the chain always held in proper tension. This chain 24 has fixed thereon a number of suitably placed and adjustably mounted cam blocks 29 which 5 are secured to the cross members of the chain which are given any desired location and shaped according to the nature of the fancy knitting to be made by the machine, as will appear below. The shape of the cam 10 13 is such that the chain 24 is advanced regularly one link for each revolution of this cam 13.

The extreme ends of the bearings 21 are connected by a fulcrum 30 on which are 15 mounted a number of bent levers 31, 32 and 33 respectively, which have their upper ends provided with nose portions 80 adapted to engage the cams 29. The lower ends of each 20 of the levers are adapted to engage and raise vertical slides 34, 35 and 36, respectively, which are slidably mounted in the frame 10 so as to have a vertical movement only. These slides are kept against their respective 25 levers by means of coil springs 37, as shown. The pawl 18 is kept against its ratchet 19 by means of a suitable coil spring 38, as shown. When this spring is removed, the pawl 18 may be separated from the ratchet 19 and then the chain 24 will not be shifted 30 and one style of knitting stitch may be repeated indefinitely by the machine 2.

The cam 11 has two faces 39 and 40 respectively, the face 39 being merely a round one which the roller 41 rests on where the 35 lever remains at rest but raised, and the cam 40 is the active face on which the roller 41 rises and falls to function. The cams 39 and 40 operate according to the position of the shaft 3, as above set forth, and either one 40 may be engaged by the roller 41 mounted on a lever 42 that is fulcrumed on the shaft 16 in the conventional manner. The lever 42 has two upwardly extending ears 43 which are perforated and provided with a pivot 45 44 on which is mounted a link 45 which is pivotally connected to a bell crank lever 46 fulcrumed at 47 between downwardly extending ears 48 which run downwardly from the frame 10 of the machine. The upper 50 end 49 of the bell crank lever 46 is adapted to bear against a slide 50 which moves between two guides 51 which are placed at the top of the frame 10 and form a part thereof. The slide 50 is provided with a laterally extending plate 52 against which the screw 9 of the shaft 4 is adapted to abut so that this shaft is moved in opposition to the spring 6 which has been described above. This slide 50 has a projecting portion 53 55 which is normally kept in contact with the upper end 49 of the bell crank lever 46 by means of two coil springs 54 which connect this slide with the fixed guides 51.

The slide 50 is split into two parts, one 65 part 55 which carries the projection 52, and

another part 56 which is adapted to abut against stops in the nature of screws projecting from the slides 34, 35 and 36 in a manner which will be described below. The two parts 55 and 56 are recessed at adjacent 70 edges to receive anti-friction rollers 57, both of which press against opposite sides of a separating cam 58, and these rollers are kept against this cam by means of coil springs 59 which connect the respective parts 55 and 56 75 together.

The part 56 has an undercut edge 60 which is adapted to abut against cap screws 61 which form stops for the slide 50 and which are placed so that their heads are 80 suitable distances from the slides 34, 35 and 36 respectively, to which they are attached and they are locked in position by means of lock nuts 62. Only one of these cap screws 85 61 acts at any one time.

The lower surface of the part 56 is secured to a guiding bracket 63 which extends diagonally and downwardly and is provided with a slot 64 near its lower end in which extends a bolt 65 which is carried by the 90 cam 58 so that this cam will be suitably guided between the rollers 57 at all times.

This cam 58 carries a pin 66 near its lower end and this pin 66 is also mounted in a lever 67 which is fulcrumed on the fulcrum 95 16 and at its free end the lever 67 is provided with a hook 68 that engages the upper end of a coil spring 69 extending to the frame 10 and secured thereto. This lever 67 also carries a cam roller 70 in the conventional manner which is adapted to engage either the frame 71 or the face 72 of the cam 12 according to the position of the shaft 3, as above set forth. The face 71 is a round one on which the roller 70 remains at one 105 level and the face 72 is the functioning face of the cam 12.

In view of the foregoing the operation of my attachment will be readily understood, it being assumed that the function of this attachment is to move the fancy needle shaft 4 in the direction of its length at appropriate times and in opposition to the spring 6. It is apparent from what has been said and described that this longitudinal movement of the shaft 4 will depend upon the movement of the slide 50 and this movement is determined by all three of the cams 11, 12 and 13, the cam 11 causing the rocking of the bell crank lever 46; the cam 12 determining 110 the position of the cam 58 which more or less elongates the slide 50, and the cam 13 causes the cam blocks 29 to come in contact with the levers 31, 32 and 33 so as to determine 115 which of the cap screws 61 will be in position to stop the sliding movement of the slide 50 and thereby limit the movement of this slide in the direction of these screws. The cams 11, 12 and 13 function together, 120 as above set forth, give a number of posi- 125 130

tions to the shaft 4 according to the pattern which is to be knitted so that a great variety of patterns may be knitted on a machine provided with my attachment by placing 5 cam blocks 29, as required, both as to number, location and shape.

While I have shown and described one embodiment of my invention, it is obvious that it is not restricted thereto, but that it is 10 broad enough to cover all structures that come within the scope of the annexed claims.

Having thus described my invention, what I claim is:

15 1. In a device of the class described, a transfer point shaft, means for shifting said shaft longitudinally, according to the pattern to be knitted, said means including a two-part slide against which said shaft is 20 held, means for separating the parts of said slide and a plurality of adjustable abutments for limiting the movement of said slide in one direction.

2. In a device of the class described, a 25 transfer point shaft, a slide for shifting said shaft longitudinally, a plurality of adjustable stops for restricting movement of said slide in one direction and means for lengthening said slide.

30 3. In a device of the class described, a transfer point shaft, a slide, means for resiliently retaining one end of said shaft against said slide, said slide having a pair of separable parts, springs for drawing said 35 parts towards one another, means slidable between the parts of said slide to separate the same, a plurality of movable stop members for restricting movement of the slide in one direction, and cam means for causing 40 movement of said stops.

4. In a device of the class described, a transfer point shaft, a slide for longitudinally shifting said shaft, said slide having a pair of separable parts, a roller on each of 45 said parts, a cam member movable between

said rollers to separate the same and lengthen the slide, a revolving drum, and endless member movable over said drum carrying a plurality of cams, levers engaged by said cams and shifted thereby, and a plurality of stops shifted by said levers, said stops being adapted to be held in the path of movement of said slide and the shaft shifted thereby and adapted to successively limit movement of said slide and shaft in one 55 direction.

5. In a device of the class described, a transfer point shaft, a slide for longitudinally shifting said shaft, means for moving said shaft in one direction, a plurality of 60 stops adapted to successively limit movement of the slide, and endless member having a plurality of cams, a plurality of levers engaged by said cams and adapted to move stops of different lengths in the path of the 65 slide on its return movement.

6. In a device of the class described, a transfer point shaft, means for shifting said shaft longitudinally, a plurality of stops of various lengths, means for successively 70 moving stops of various lengths in the path of movement of said shaft-moving means, said shaft-moving means comprising a slide composed of two separable parts, and means movable between said parts to separate the 75 same.

7. In a device of the class described comprising a transfer point shaft, a slide, means for holding said shaft against the slide, said slide having a pair of separable parts, means 80 for holding said parts together, movable means for separating said parts, a plurality of movable cam members and means for carrying the same, a plurality of movable stops for limiting movement of the slide 85 and means actuated by said cam members for shifting the stops.

Signed at the city, county and State of New York, this 17th day of June, 1921.

LOUIS TLUCKA.
